(57) **CLAIM**

The ornamental design for a self-service terminal, as shown and described.

DESCRIPTION

Fig. 1.1 is a perspective view of a self-service terminal;

Fig. 1.2 is a bottom view thereof;

Fig. 1.3 is a top view thereof;

Fig. 1.4 is a rear view thereof;

Fig. 1.5 is a right side view thereof;

Fig. 1.6 is a front view thereof; and

Fig. 1.7 is a left side view thereof.

The broken lines in the drawings show portions of the self-service terminal that form no part of the claimed design.
